WATER CLOSET

Martin J. Kumnick, Englewood Cliffs, N. J.

Application June 25, 1949, Serial No. 101,293

19 Claims. (Cl. 4-77)

1

The present invention represents what is believed to be a substantial innovation in and departure from conventional self-pumping water closets; and while applicable to many types of water closet installations, it finds particular usefulness in situations such as aboard ships, where considerable variation in both inlet and outlet pressure heads may exist, as in positions above or below the sea water level; or where economy of size or structural and operational simplicity become important considerations.

Self-pumping water closets of the prior art, which employ centrifugal type pumps, are frequently lacking in the necessary lifting power to pump the discharge material through a discharge point substantially above the flushing bowl. The rotary, sliding vane type water closets are prone to exhibit shortcomings in that material tends to wrap around the rotor. The plunger or piston type water closets generally have so small a piston displacement that much of the material will pull only part way through the valve on the working stroke, thus preventing the valves from properly closing.

My invention is intended to remedy the various defects outlined above, and, to this end, has for its general object the utilization of a plunger-type pump of sufficient displacement so as to complete the flushing operation in one complete plunger cycle, thus removing all the material from the flushing bowl with sufficient power to discharge it more than four feet above the bowl level.

In the following specification and drawings, I shall describe one embodiment which will afford a better understanding of the nature of my invention together with further objects and advantages thereof.

In the drawings:

Fig. 1 is a cross-section through the water closet showing the plunger in the "down" or "ready" position, i. e., in a position in which it is ready to start a flushing cycle;

Fig. 2 is a detail of the input valve in the closed position showing the magnetically-controlled safety latch;

Fig. 3 is a partially sectional view along the line 3-3 of Fig. 1;

Fig. 4 is a horizontal cross-section of the switch control box and

Figs. 5, 6, 7, 8, 9 and 10 are circuit diagrams showing the successive energizations of the coils.

The device shown is essentially an electromagnetically operated self-pumping water closet utilizing a mechanical piston or plunger 1 adapt-

2

ed to pass over two preferably concentric diamagnetic inner tubes 2 and 3, the inner tube 2 being adapted to allow the passage of waste material from the flushing bowl 4, through the discharge chamber 5 and through the discharge valve 6, and the outer tube 3 being adapted to permit the passage of flushing fluid from the intake chamber 7 through the electromagnetic intake valve 8, through the passages 9, 10 to the upper portion of the outer concentric tube 3 through the ports 11 into the space 12 above the piston 1.

The water closet is in the "ready" position with the plunger 1 in the "down" position, as shown in Fig. 1, the space 12 above the plunger 1 being full of flushing fluid to the level indicated in Fig. 1. The intermediate coil 14 is magnetized first. This partly raises the plunger 1 in the cylinder 35. This coil is then de-energized simultaneously with the energization of the top coil 13 which operates to complete the upward travel of the plunger (line 1a) forcing the fluid in the space 12 above the plunger 1 into the flushing bowl 4 through the valve 16.

The reduction in pressure thus created in the cylinder 35 below the plunger 1 as it rises causes all matter in the bowl 4 to discharge through the anti-splash valve 31, tube 2 and valve 32 into the discharge chamber 5, waste fluids filling the space below the plunger 1, and solid matter being confined to discharge chamber 5 by the stationary baffles 33 and 33a as hereinafter to be discussed.

When the plunger 1 is in the "up" position (line 1a), the center solenoid 14 is then energized and the top coil 13 de-energized. This causes the plunger 1 to begin its downward travel. The center coil 14 is then de-energized simultaneously with the energization of the bottom coil 15. This

causes the plunger 1 to resume its original position, forcing the waste material in the discharge chamber 5 out through the discharge valve 6. As the plunger 1 makes its downward stroke a reduction of pressure in the cylinder space 12 above the plunger 1 causes flushing fluid to pass from the intake chamber 7 through the intake valve 8, through the passages 9 and 10, through the tube 3 and the ports 11 into the space 12 above the plunger 1, leaving the device ready for the next operation.

It will be understood by one skilled in the art that the system may be so designed as to permit one complete flushing cycle to take place in a predetermined period of time and that this period of time may be varied by any well-known means.

to correspond to variations in intake and discharge heads. For example, I use a 5 to 10 second period of time.

The flushing fluid in the intake chamber 7 is prevented from entering the intake tube 3 by the electromagnetically controlled valve 8 until the plunger 1 is in its uppermost position. This valve 8 is an ordinary flap-type, weight-loaded, gravity valve secured by a latch 17 hinged at 18 and pinned to an armature 19 at 20. The armature 19 is pivotally fixed at its upper end at point 21 by suitable means as by attachment to a projection of tube 3, and is spring-biased by tension spring 23 to rotate clockwise as seen in Fig. 2 so that it tends normally to close the intake valve 8 by forcing the latch 17 against it. When the plunger 1 moves to the upper position (line 1a of Fig. 1) the magnetic flux through armature 19 thereby increases sufficiently that the armature 19 is magnetically attracted in such manner that it rotates counterclockwise about point 21 against the tension of spring 23 until its lower end reaches the point 24. This causes the latch 17, which is pivoted at point 18 and rotatably pinned to the armature 19 at point 20, to swing to a position generally parallel to the longer arm of the armature 19, thus permitting the intake valve 8 to open. The valve 8 is in effect a weight-loaded, flap-type valve.

It will be understood by one skilled in the art that by proportioning the amounts and positions of the magnetic members in the magnetic fields of the coils 13, 14 and 15, the magnetic reluctances in the two extreme positions of the armature 19 will be such that the armature 19 will be attracted upward when the plunger 1 is in its upper position and not attracted when the plunger 1 is in its lower position. In any event, since the intent is that the intake valve 8 be closed when the plunger 1 returns to its lower position, the closure of that valve may also be accomplished by proper de-energization of the lower coil 15 when the armature will return to its lower position.

Referring to the drawings in more detail, 4 denotes a flushing bowl which may be one having an oval flushing rim of vitreous china, or of any diamagnetic metal, with flushing water passages 25 and rim 29 formed within the bowl to eliminate external piping. At the top of the flushing water passage 25 is the bowl input valve 16 which may be a flap-type, gravity or spring-closing valve. This may be held open by a "push-in" plunger 26. This plunger 26 when fully advanced, will hold the input valve 16 open, thus permitting maximum bowl discharge with minimum flushing water input when flushing fluid has been put into the bowl 4 by other means. Surrounding the plunger 26 is a threaded member 27 which may be adjusted to advance or retard the position of the stud 28 and thereby may be used to hold the valve 16 slightly away from its seat thereby permitting air to enter the space 12 above the plunger 1 on the flushing fluid suction stroke, or downward stroke, permitting control of the quantity of flushing fluid supplied to the space 12 for later discharge.

Fastened to the bowl, at its underside, is a thin-walled tube 35 preferably of diamagnetic metal. This tube 35 extends to the base plate 30 and is made water-tight at both ends by gaskets 35a. The base plate 30 may be a casting of diamagnetic metal which supports the entire device. Concentric with the tube 35 and joined to the base plate 30 and to the underside of the flushing bowl

4, being made water-tight at that point by the anti-splash valve 31, are two tubes 2 and 3, the outer tube 3 having water ports 11 at its upper end and containing the steel strip 22, and the inner tube 2 being adapted to receive the discharge of material from the bowl 4.

The anti-splash valve 31 is preferably a double-tiered, slotted cone having four sectional flaps arranged so that a flap of one cone half overlaps a flap of the other cone. This cone is preferably made of a pliable material such as neoprene. Thus the valve section flaps push open to permit the passage of waste materials from the flushing bowl 4. This valve 31 prevents material in the discharge chamber 5 from resurging into the bowl 4 when the plunger 1 is on its down stroke in the event that the discharge valve 32 fails to close completely.

Positioned directly alongside the discharge chamber 5 and within the base 30 is the intake chamber 7. This intake chamber 7 is adapted to receive flushing fluid from the sea or from a fluid storage tank by pipe 82 and is adapted to feed flushing fluid to the intake tube 3 by the intake valve 8 hereinbefore discussed. The solenoid valve 80 is preferably positioned near the opening 81 of the intake chamber 7 outside the point where the water supply pipe 82 enters the chamber 7. It should be understood that the solenoid valve 80 is closed while the intake valve 8 is closed, and is adapted primarily to be used as a safety valve when the water-closet is operating at extreme heads both intake and discharge.

Positioned directly below the discharge tube 2 and within the base 30 is the discharge chamber 5. This chamber lies below the check valve 32 and contains the slotted baffles 33 and 33a hereinafter to be described.

Adapted to slide between the center and the outer concentric tubes 3 and 35 by a center opening is a magnetic plunger 1, preferably of soft steel, having each end coned in towards the plunger center. The entire plunger 1 preferably is electroplated to retard corrosion and provision is made for sealing the working surfaces between plunger 1 and the tubes 35 and 3 by placing sealing rings 34 at the top and bottom of the outside surfaces of the plunger 1 and sealing rings 36 on the inside surface of the center opening of the plunger 1.

On the outside of the cylinder 35 are placed three electromagnetic coils 13, 14 and 15 which may be adapted to be energized in a predetermined order by any well-known series of electromagnetic switches, Fig. 4, which utilize the ship's or vehicle's electric current and which may be operated by a cam handle 45 placed on a switch box 37. The switch box 37 which also controls solenoid valve 80 may be positioned on the wall of the stateroom or closet within easy reach of the operator. A preferred embodiment employed will be described hereafter.

At the base of the discharge tube 2 between the tube 2 and the discharge chamber 5 is a discharge check valve 32 which may be a flap-type, spring-closing valve hinged to the base plate 30 at point 38; the spring 39 being connected to the stationary baffle 33.

Fastened to the raised part of the base 30 at points 40 and 41 are two stationary baffles 33 and 33a made of diamagnetic metal. These baffles are nearly as wide as the discharge chamber 5. The lower ends of these baffles 33 and 33a are slotted lengthwise so as to create strips, these strips being twisted at their upper ends to form

tines. This permits the waste fluid to pass under the plunger 1 and confines the solids to the discharge chamber 5, all the waste material being discharged through valve 6 by the downward stroke of the plunger 1.

At the outlet end of the discharge chamber 5 is a flap-type, weight-loaded, gravity or spring-closing sea-discharge valve 6 normally held closed by the pressure of the sea water head if such exists, or held closed by its own weight, or by spring 42 if there is no back pressure, and adapted to open for discharge on the return stroke of the plunger 1.

One embodiment of the means I employ to energize the coils 13, 14 and 15 is substantially as follows: Affixed to the stateroom wall sufficiently near the water-closet so as to be within easy reach of the operator is a switch box 37 containing a rotary cam 44 adapted to rotate through an angle of 360° by any well-known mechanical or electrical means, a cam handle 45 adapted to operate said means, armatures 46, 47, 48, 49 and 50, normally spring-biased in a clockwise direction by pressure of the springs 51a, 52a, 53a, 54a, 55a on the fixed studs 51, 52, 53, 54, 55 and cam followers 56, 57, 58, 59 and 60 affixed to the armatures 46, 47, 48, 49 and 50. This switch, Fig. 4, is in circuit with a current source which may be the ship's current and is also in circuit with the three coils 13, 14 and 15 disposed around the cylinder 35. Preferably, in the circuit are a conventional field discharge resistor 61, a condenser 62 and a magnetic blow-out coil 63 adapted to reduce arcing and induced voltages in the coils 13, 14 and 15 when any of the said coils 13, 14 or 15 is de-energized.

The method of operation of the control system is as follows: The cam 44 is in the initial position when shoulder 66 rests between the points 64 and 65 (Fig. 4), no coil being then energized. In this position line 67 and line 68 are open at points 69 and 70, no current flowing (Fig. 10). This prevents any leakage of current through the system. The cam is then rotated by any well-known means, as for example by a spring, through an angle of 360° during a predetermined period of time, for example, 5 to 10 seconds. This period of time is the same as that through which the plunger makes its complete flushing cycle and may be varied by any well-known means to correspond to variations in intake and discharge heads. When the shoulder 66 of the cam 44 reaches the point shown in Fig. 4, the spring 51a forces the cam rider 56 down to the lower level of the cam 44 closing the contact points 67 and 69, the cam rider 60 having ridden up on the upper level of the cam 44 over the shoulder 66a closing the contact points 68 and 70. The current then follows the path through intermediate coil 14 in Fig. 5.

The cam shoulder 66 next reaches the point, 51a. This closes the points 72 and 73, the points 67 and 69 and 68 and 70 remaining closed. The current then flows as shown in Fig. 6 which has the effect of energizing the top coil 13 and de-energizing the intermediate coil 14.

As the cam shoulder 66 continues its rotary path the various contact points 75, 76 and 78 and 79 close successively causing the current to flow as in Figs. 7 and 8. Just before cam shoulder 66 reaches point 60a, cam rider 56 rides up to the upper level of cam 44 on cam shoulder 66a. This has the effect of opening points 67 and 69, points 68 and 70 remaining closed. No 75

current flows as shown in Fig. 9. Cam shoulder 66 next passes point 60a, at which time it reaches its initial position as hereinbefore shown. The purpose of having lines 67 and 68 both open at the initial position, i. e., when cam shoulder 66 rests between points 64 and 65 is to prevent any leakage of current through the system. Thus the coils 13, 14 and 15 are energized in the following order: the intermediate coil, the top coil, the intermediate coil and the lower coil. The plunger is thus carried through one complete flushing cycle.

A solenoid valve 80 is positioned near the opening 81 of the intake chamber 7 outside the point where the water supply pipe 82 enters the chamber. This solenoid valve 80 is controlled electrically by the switch (see Fig. 4) and is adapted to open when the cam shoulder 66 successively reaches the points 58a and 59a, the current flowing as shown in Figs. 7 and 8.

I claim:

1. A water closet comprising a bowl, a discharge tube and an intake tube connected to said bowl, a flushing mechanism for forcing fluid through said intake tube into said bowl for discharge through said discharge tube, comprising a reciprocatable electromagnetic plunger, electromagnetic means for reciprocating said plunger, and means for energizing said means whereby said plunger may be caused to reciprocate cyclically to force fluid into said bowl during one-half of its reciprocatory cycle.

2. A water closet as in claim 1 including an electromagnetically operated intake valve responsive to the energization of said electromagnetic means for controlling the influx of flushing fluid to said intake tube.

3. A water closet as in claim 2 including means for preventing the resurgence of discharge material through said discharge tube.

4. A water closet as in claim 1 including means for preventing the resurgence of discharge material through said discharge tube.

5. A water closet comprising a bowl, a discharge tube, and an intake tube connected to said bowl, a flushing mechanism for forcing a flushing fluid through said intake tube into said bowl for discharge through said discharge tube, comprising a reciprocatable electromagnetic plunger, a plurality of electromagnetic coils positioned along the path of said plunger for reciprocating said plunger, and means for energizing said coils in a predetermined sequence whereby said plunger may be caused to reciprocate cyclically to force fluid into said bowl during one-half of its reciprocatory cycle.

6. A water closet as in claim 5 in which said means for energizing said coils comprises a rotatable cam, a plurality of switch opening and closing members including cam riders adapted to cooperate with said cam, said members being connected in circuit with said coils.

7. A water closet as in claim 5 including an electromagnetically operated intake valve responsive to the energization of said electromagnetic coils for controlling the influx of flushing fluid to said intake tube.

8. A water closet as in claim 7 including means for preventing the resurgence of discharge material through said discharge tube.

9. A water closet as in claim 5 including means for preventing the resurgence of discharge material through said discharge tube.

10. A water closet comprising a bowl, a discharge tube positioned directly below said bowl, an intake tube concentric with said discharge

tube, a flushing mechanism for forcing flushing fluids through said intake tube into said bowl for discharge through said discharge tube comprising a reciprocatable electromagnetic plunger adapted to operate concentrically with said discharge and intake tubes, a plurality of electromagnetic coils positioned along the path of said plunger for reciprocating said plunger and means for energizing said coils in a predetermined sequence whereby said plunger may be caused to reciprocate cyclically to force flushing fluid into said bowl during one-half of its reciprocatory cycle.

11. A water closet as in claim 10 in which said means for serially energizing said coils comprises a rotatable cam, a plurality of switch opening and closing members including cam riders adapted to cooperate with said cam, said members being connected in circuit with said coil.

12. A water closet as in claim 10 including an electromagnetically operated intake valve responsive to the energization of said electromagnetic coils for controlling the influx of flushing fluids to said intake tube.

13. A water closet as in claim 12 including means for preventing the resurgence of discharge material through said discharge tube.

14. A water closet as in claim 10 including means for preventing the resurgence of discharge material through said discharge tube.

15. A water closet comprising a bowl, a cylinder positioned below said bowl, a discharge tube positioned below said bowl and an intake tube positioned below said bowl, both intake and discharge tubes being concentric with and within said cylinder, a flushing mechanism for forcing flushing fluid through said intake tube into said bowl for discharge through said discharge tube comprising a reciprocatable electromagnetic plunger adapted to operate between said intake tube and cylinder, a plurality of electromagnetic coils positioned along the path of said plunger

and outside said cylinder for reciprocating said plunger, and means for energizing said electromagnetic coils in a predetermined sequence whereby said plunger may be caused to reciprocate cyclically to force flushing fluid into said bowl during one-half of its reciprocatory cycle.

16. A water closet as in claim 15 in which said means for serially energizing said coil comprises a rotatable cam, a plurality of switch opening and closing members including cam riders adapted to cooperate with said cam, said members being connected in circuit with said coils.

17. A water closet as in claim 15 including an electromagnetically operated intake valve responsive to the energization of said electromagnetic coils for controlling the influx of flushing fluid to said intake tube.

18. A water closet as in claim 17 including a valve normally biased to close the end of said discharge tube for preventing the resurgence of discharge material through said discharge tube.

19. A water closet as in claim 15 including means for preventing resurgence of discharge material through said discharge tube.
